UNITED STATES PATENT OFFICE.

BERNARD BURNS, OF TORONTO, ONTARIO, CANADA.

KEYBOARD.

Application filed March 17, 1924. Serial No. 699,954.

My invention relates to key-boards and has for its particular object to provide a key-board of a supplemental character which may be employed in connection with linotype or other type setting machines or with typewriters or the like whereby the number of keys may be increased and the arrangement of the keys determined without regard to the fixed arrangement of the main key-board.

When this invention is employed in connection with linotype machines for instance having a double magazine, all of the characters carried in both magazines could be shown eliminating the necessity of the operator remembering their position as is customary at present.

With my invention it is possible to maintain a uniform arrangement of key-boards on, for instance, all of the composing machines, typewriters or the like in use in any one establishment, irrespective of the key-board arrangements of the several machines and further to provide means for controlling any of the keys from the side thereby producing a point of influence at a given place.

The construction of the device is such that it may be easily and quickly manufactured and assembled so as to produce the desired key-board arrangement and may furthermore be readily attached to the standard types of key-board without any material alteration thereto.

The invention further consists in the novel combination, construction and arrangement of parts all of which will be more apparent hereinafter as this description proceeds, especially when considered in connection with the accompanying drawings wherein:

Figure 1 is a front elevation, partly in section of my improved key-board as it appears when employed in connection with the key-board of a linotype machine;

Figure 2 is a plan view of the key board partly broken away showing the relative positions of the keys of the two key-boards;

Figure 3 is a transverse sectional view taken substantially on the plane indicated by line 3—3 in Figure 2;

Figure 4 is a fragmentary detail perspective view of the connecting means between the supplemental and main key-boards, cer-

tain parts being omitted for the sake of clearness;

Figure 5 is a fragmentary detail view;

55

Figure 6 is a fragmentary detail view;

Figure 7 is a fragmentary perspective view of a detail of construction; and

Figure 8 is a similar view.

Referring now more particularly to the drawings wherein like reference characters indicate like parts it will be noted that there is illustrated a portion 10 of a machine which constitutes the frame of the key-board. The invention is illustrated as used in connection with the key-board of a linotype machine but as this description proceeds it will become readily apparent to those skilled in this art that its use is not limited to this character of machines but that it may be employed with equal facility to all types of composition and typewriting machines. The reference character 11 indicates the standard keys of a linotype machine which, as shown in Fig. 2, are customarily disposed in a set 65 70 75 prearranged order and are furthermore usually arranged in echelon.

The supplemental key-board constituting this invention consists preferably of a frame 12 supporting the supplemental keys and 80 also the operating means between the supplemental and main keys, this frame being adapted to rest upon and be supported by the frame 10 of the machine to which it is attached. For detachably supporting the 85 supplemental frame upon the main frame 10 there is preferably provided at each side of the frame 12 angular clips 13 rigidly secured to the frame 12 and adapted to rest with their angular ends upon the elevator 90 shaft bracket 14 of the machine. In Fig. 7 this construction for one side of the machine is illustrated and it is of course understood that this arrangement is duplicated at the other side of the machine at the front there- 95

of. At the rear the frame 12 is extended downwardly at both sides thus producing relatively narrow extensions 15 to which there is secured a second extension 16 notched as at 17. The reference character 18 indicates a guide plate for the main key levers 11 and in positioning the supplemental key-board upon the main key-board the front is first caused to rest upon the ele- 100

vator shaft brackets 14 as previously described whereupon the notches 17 of the extension 16 are caused to engage the edge of the key lever guide plate 18 whereupon the supplemental key-board is held rigidly in place. It should be noted that each extension 15 of the frame 12 has the end 19 thereof angularly disposed to act as stops to limit the downward movement of the supplemental key-board.

Arranged longitudinally of the frame 12 are a plurality of shafts 20 adapted to support the keys 21 constituting the supplemental key board. While each longitudinal row of keys is mounted on a common shaft 20 each of these keys is operable independently and for this purpose the keys 21 are loosely mounted on the shafts 20. While this invention contemplates a key-board with seven longitudinal rows of keys this number may be altered or changed as circumstances and requirements dictate. In Fig. 3 the lowermost shaft 20' supports the space bar 22 which preferably extends the entire longitudinal length of the key-board.

Also arranged longitudinally of the frame 12 is a pair of supporting rods 23 and upon these rods there is adapted to be positioned a plurality of bars 24. These bars are preferably arranged in groups of six in number and supported on edge upon the bars 23 whereby they may be longitudinally displaced transversely with reference to the frame 12. These bars are arranged in groups of six, when the key-board is used in connection with a linotype machine because the main keys of the linotype machine are arranged in six longitudinal rows. The bars 24 are adapted to be longitudinally displaced by means of the keys 21 and for this purpose these bars are each provided with a pin 25 adapted to be engaged by the depending projection 26 of the associated key 21. It should be noted that the depending flange or projection 26 of each key 21 is of sufficient width to engage a pin 25 on any one of the group of six bars 24 so that the universality of the machine and the ease with which it may be assembled to suit the particular requirements is insured.

For the purpose of adjusting the machine to different touches there is provided adjacent the rear of the frame 12 a buffer bar 27 supported by means of rods 28 which pass through the frame 12 and are provided each with a nut 29. The rods 28 pass freely through the frame 12 and a coil spring 30 is arranged on each rod 28 between the casing 12 and the buffer bar 27. Tension of the spring 30 may be regulated by the nut 29. Consequently during the displacement of the bars 24 they will engage the buffer bar 27 and by this means the touch of the key-board may be regulated and the parts assisted in returning to normal position.

Also mounted longitudinally of the frame 12 are a plurality of rods 31, these rods being preferably ninety in number. It is upon these rods that the levers affording connection between the supplemental and main keys are mounted. By reference to Fig. 4 the construction and arrangement of the operating levers will be more readily apparent. In this figure only certain of the keys 21, bars 24 and rods 31 have been illustrated. The connection between a key 21 and a key 11 is constituted, in addition to the parts already recited, by a bell crank lever 32 mounted on a rod 31 and engaging with its upper end a notch 33 in a bar 24. A second bell 80 crank lever 34 also attached to the rod 31 engages with its free end the key 11 to be operated. Thus when the key 21 is depressed the bar 24 is displaced in the direction of arrow A in Fig. 4 whereupon the bell crank 85 lever 32 is rocked in the direction of arrow B, this rocking motion being transmitted through the rod 31 to the bell crank lever 34 which is rocked in the direction of arrow C whereupon the key 11 is depressed. As mentioned hereinbefore the buffer bar 27 will assist in returning the parts to normal position but this return movement is dependent largely upon gravity.

It is to be understood that the bars 24 are arranged in groups of six and that the depending flanges 26 of the keys 21 are of sufficient width to engage the projecting pin 25 of any one of the associated group of bars 24 therefore, inasmuch as each bar 24 may be notched opposite any of the longitudinal rods 31 and furthermore inasmuch as the bell crank lever 34 may be placed at any longitudinal position on any of the bars 31 it is possible from any key 21 to actuate any main key 11. Therefore, in assembling the supplemental key-board any desired arrangement of the supplemental keys may be resorted to irrespective of the main key-board arrangement. Furthermore, additional control may be provided by adding new keys 21, additional bars 24 and additional bell crank levers 32. Thus duplicate or even triplicate control of the important keys of the main key-board is possible from any desired point of the supplemental key-board.

The universality of the supplemental key-board and the number of key-board arrangements of which the same is capable thus producing the desired combination or position of keys is quite obvious when it is remembered that there are ninety of the rods 31 with a similar number of bell crank levers 32, thus giving ninety positions. There are ninety of the bars 24 suitably notched for connection with any of the bell crank levers 32, thus giving ninety positions. The depending projection 26 of each key 21 is capable of engaging any one of the six associated bars 24, thus producing six positions

so that the number of positions possible may be computed as ninety times ninety times six.

Obviously, the supplemental key-board may be extended out beyond the frame on the right so that sufficient keys may be added to render possible any practical key-board arrangement. However, without extending the key-board beyond the dimensions shown in the drawing, it is thought that the supplemental key-board will contain enough keys for all practical purposes. The space bar illustrated at 22 is connected to the bar 24 and bell crank levers to actuate the main space bar in the customary manner.

From the foregoing it will be immediately apparent that I have provided a supplemental key-board which may be cheaply and durably manufactured and easily attached to standard types of key-boards without materially altering the construction of the same. The supplemental key-board is so arranged as to facilitate assembling whereupon the objects of the invention may be accomplished and furthermore the parts thereof may be readily replaced so that the same may be kept in perfect condition. The weight of the operative connections between the supplemental and main keys is borne by the frame and not by the main keys so that the operation of the linotype or other machine is not impaired in the least.

While one embodiment of my invention has been described and illustrated herein in some detail, it is not intended that my invention be unnecessarily limited but reservation is made to make such changes as may come within the purview of the accompanying claims.

Having thus described my invention, what I claim is:

1. The combination with a key-board comprising a plurality of main keys, of a supplemental key-board including a plurality of supplemental keys, a frame, a plurality of rods mounted in said frames, and means including a plurality of bell crank levers adjustably mounted on said rods for operating said main keys by said supplemental keys whereby a plurality of key-board combinations are possible.

2. The combination with a key-board including a plurality of main keys, of a supplemental key-board, said supplemental key-board comprising a frame, a plurality of supplemental keys supported thereon, a plurality of longitudinally extending rods mounted in said frame, a plurality of transversely arranged bars, operated by said supplemental keys, and means carried by said rods and operated by said bars for actuating said main keys, said means being adjustable whereby a plurality of key-board combinations are possible.

3. The combination with a key-board including a plurality of main keys, of a sup-

plemental key-board, said supplemental key-board comprising a frame, a plurality of supplemental keys supported thereon, a plurality of longitudinally extending rods mounted in said frame, a plurality of transversely arranged bars operated by said supplemental keys, and bell crank levers carried by said rods and operated by said bars for actuating said main keys, said means being adjustable whereby a plurality of key-board combinations are possible.

4. The combination with a key-board including a plurality of main keys, of a supplemental key-board comprising a frame, a plurality of supplemental keys mounted on said frame, a plurality of longitudinally arranged rods supported by said frame, a plurality of groups of transversely arranged bars slidably mounted on said frame, means operatively connecting said supplemental keys to said bars for displacing the same transversely to said frame, and bell crank levers mounted on said longitudinally arranged rods and engaging said bars and main keys whereby said main keys may be operated by said supplemental keys.

5. The combination with a key-board including a plurality of main keys, of a supplemental key-board comprising a frame, a plurality of supplemental keys mounted on said frame, a plurality of longitudinally arranged rods supported by said frame, a plurality of groups of transversely arranged bars slidably mounted on said frame, means operatively connecting said supplemental keys to said bars for displacing the same transversely to said frame, a plurality of bell crank levers mounted on said rods and engaging said bars, and a plurality of additional bell crank levers mounted on said rods and engaging said main keys as and for the purpose described.

6. The combination with a key-board including a plurality of main keys, of a supplemental key-board comprising a frame, a plurality of supplemental keys mounted on said frame, a plurality of longitudinally arranged rods supported by said frame, a plurality of groups of transversely arranged bars slidably mounted on said frame, means operatively connecting said supplemental keys to said bars for displacing the same transversely to said frame, said bars being notched, a plurality of bell crank levers mounted on said rods and engaging the notches in said bars, whereby said main keys may be actuated by depressing said supplemental keys.

7. The combination with a key-board including a plurality of main keys, of a supplemental key-board comprising a frame, a plurality of supplemental keys mounted on said frame, a plurality of longitudinally arranged rods supported by said frame, a plurality of groups of transversely arranged

bars slidably mounted on said frame, means operatively connecting said supplemental keys to said bars for displacing the same transversely to said frame, said bars being notched, a plurality of bell crank levers slidably adjustable on said rods and engaging the notches in said bars, whereby said main

keys may be actuated by depressing said supplemental keys in dependence upon the adjusted position of said levers.

The foregoing specification signed at Toronto, Canada, this 11th day of February, 1924.

BERNARD BURNS.
